UNITED STATES PATENT OFFICE.

WILLIAM H. TOMEY, OF WALLINGFORD, CONNECTICUT, ASSIGNOR TO THE
R. WALLACE & SONS MANUFACTURING COMPANY, OF SAME PLACE.

DESIGN FOR A SPOON.

SPECIFICATION forming part of Design No. 22,498, dated June 6, 1893.

Application filed April 21, 1893. Serial No. 471,345. Term of patent 3½ years.

To all whom it may concern:

Be it known that I, WILLIAM H. TOMEY, of Wallingford, in the county of New Haven and State of Connecticut, have invented a new 5 Design for a Spoon; and I do hereby declare the following, when taken in connection with the accompanying drawing and the letters of reference marked thereon, to be a full, clear, and exact description of the same, and which 10 said drawing constitutes part of this specification, and represents a face view.

This invention relates to a design for spoons, and consists in the configuration and ornamentation as shown in the accompanying 15 illustration and hereinafter described.

The end of the handle is composed of a bust A, of Christopher Columbus, wearing a cap or turban, and supported upon a geographical globe B, overlaid upon its outer edge with 20 sprays of laurel leaves C, and upon its inner

edge with a ribbon D, and another spray of laurel leaves E. The globe is supported upon the capital E', of a pillar, the said capital being rested upon a long scroll F, in the roccoco style of ornamentation. This scroll terminates 25 at its inner end in a shield G, displaying the arms of Spain. This shield is attached to the bowl H of the spoon, which contains in relief the pictorial representation of Columbus before the King and Queen at Barcelona. 30

I claim—

The design for a spoon as described and shown in the accompanying illustration.

In testimony whereof I have signed this specification in the presence of two subscribing witnesses.

WILLIAM H. TOMEY.
